CLAIM

The ornamental design for an LED lamp, as shown.

DESCRIPTION

FIG. 1 is a bottom perspective view of an LED lamp showing my new design;

FIG. 2 is a bottom elevational view thereof;

FIG. 3 is a right side view thereof, the left side being a mirror image;

FIG. 4 is a top view thereof;

FIG. 5 is a front view thereof, the back being a mirror image; and,

FIG. 6 is a top perspective view thereof.

The broken lines showing LEDs form no part of the claimed design.
